Attorney.

UNITED STATES PATENT OFFICE.

DORR H. HADSELL, OF BROCKTON, MASSACHUSETTS, ASSIGNOR OF ONE-HALF TO T. D. BARRY, OF BROCKTON, MASSACHUSETTS.

WELT-BEATER.

No. 886,292.

Specification of Letters Patent. Patented April 28, 1908.

Application filed December 10, 1907. Serial No. 405,904.

To all whom it may concern:

Be it known that I, DORR H. HADSELL, a citizen of the United States, residing at Brockton, in the county of Plymouth and 5 State of Massachusetts, have invented an Improvement in Welt-Beaters, of which the following description, in connection with the accompanying drawings, is a specification, like letters on the drawings representing like 10 parts.

My invention is an improved welt beater whereby greater speed, finish and nicety of work may be produced, and more satisfactory results attained.

15 I have found that the various improper movements of the shoe and the various defective results which are commonly experienced, may be obviated by applying oil in the right amount in the critical place between 20 the upper and welt, and preferably depending upon the beating action of the hammer to spread the oil slightly toward the seam and over the upper surface, and accordingly 25 my invention resides in the particular combination which embodies the above.

In the drawings, I have shown in side elevation a usual Goodyear welt beater containing my improvement.

For the purposes of this application it is 30 unnecessary to show and explain all the constructional details of the machine excepting so far it relates to my improvement.

The frame 1 and head 2 carry a heavy 35 vibrating arm or lever 3 in whose outer end is the welt beater or hammer 4, said arm being driven by any suitable means as by an eccentric 5.

A slasher or knife for cutting the welt is indicated at 6.

40 Beneath the hammer is an anvil 7 having a flat top surface on which the welt 8 may rest, and a pointed nose 9 to enter between the welt 8 and the upper 10 and follow along next to the seam which joins the welt and 45 upper, said anvil having a curved under surface for bearing on the upper and receiving the hard guiding pressure of the last 11.

A suitable oil supply 12 is mounted at a 50 sufficient height to give a proper head to the flow of oil, controlled by a cock 13, said oil being conducted by a pipe 14 to the anvil 7, which it enters at 15, said anvil being provided with a duct 16 for the delivery of the oil. Just back of the toe or nose 9 of the

anvil at the point where the pressure of the 55 last and upper are apt to be the hardest, or in other words, at about midway of the curved under surface of the anvil, I provide a small outlet opening 17 from the duct 16, which permits an exceedingly small but continuous amount of oil to ooze forth.

With the oil duct opening located as described, the result is that at each stroke or blow of the hammer 4 upon the welt, an exceedingly small amount of oil is spread in a 65 thin film over the anvil and adjacent surface of the upper toward the seam, so that this particular region of the anvil and the leather are maintained sufficiently smeared, but without any danger of either too much or too 70 little oil for the best results.

By locating the oil duct and opening in the particular manner described, I take advantage of the striking action of the hammer to accomplish all the spreading of the oil that is 75 desirable.

From the foregoing description it will be obvious that as the operator presses the last and its contained upper and welt hard against the anvil, the delicate ooze of oil from the 80 outlet 17 will be spread in a thin coating over the adjacent surfaces.

Having described my invention, what I claim as new and desire to secure by Letters Patent, is,

85 A welt beater, comprising an anvil having a top surface for holding the welt in position to be beaten out, a nose to follow the seam and enter between the welt and upper, and a curved under surface to receive the adjacent 90 upper as it is hard pressed by the edge of the last in the process of welt beating, a source of oil supply, a tube leading therefrom to said anvil, said anvil being provided with an internal duct opening in the midst of said 95 curved under surface, and a vibrating hammer above said anvil, operating to beat out the welt on the upper side of the anvil and coöperate with the work and anvil in spreading the oil on the shoe upper and under side 100 of the anvil as it oozes from said opening.

In testimony whereof, I have signed my name to this specification, in the presence of two subscribing witnesses.

DORR H. HADSELL.
